[57] ABSTRACT

The present invention is directed to a necktie which consists of a body portion detachably secured to the collar of a shirt by a flexible spring wire member which engages over the neckband of the shirt and under the collar tabs of the shirt. The body member is provided with detachable fasteners and second body carrying wings detachably secured to the body member completely covering the body member and supporting wires.

BACKGROUND OF THE INVENTION

Field of the Invention

The present invention relates to decorative neckties which are detachably secured to the collar of a shirt.

SUMMARY OF THE INVENTION

The present invention includes a body member having 10 separable fasteners mounted thereon. The body member is detachably mounted on the front of a shirt at the collar by means of a flexible spring wire secured to the body member with the wire having parts engaging over the neckband of the collar and other portions extending under the collar tabs. A second body carrying wings is detachably secured to the body member completely covering the body member and the wires.

The primary object of the invention is to provide a necktie which is detachably secured to the collar of a shirt and which has interchangeable detachable wing portions.

Other objects and advantages will become apparent in the following specification when considered in the light of the attached drawings.

BRIEF DESCRIPTION OF THE DRAWINGS

FIG. 1 is a front elevation of the invention with the collar shown in broken lines;

FIG. 2 is a rear elevation of the invention with the collar shown in broken lines;

FIG. 3 is a side elevation of the invention removed from the shirt;

FIG. 4 is a front elevation of the body member with the second body and wings removed; and

FIG. 5 is an enlarged fragmentary sectional view of the detachable connection between the body member and the second body.

DESCRIPTION OF THE PREFERRED EMBODIMENT

Referring now to the drawings in detail wherein like reference characters indicate like parts throughout the several figures the reference numeral 10 indicates generally a necktie constructed in accordance with the invention.

The necktie 10 is adapted for use with a conventional shirt collar generally indicated at 11 having a neckband 12 supporting a pair of collar tabs 13, 14.

The necktie 10 includes a body member 15 formed of any suitable material such as plastic, hard rubber, or the like. The body member 15 has a generally flat front surface 16 having a pair of female snap sockets 17 mounted therein.

A spring wire 18 has a loop 19 molded into the body 15 and engaging about a pin 20 extending through the body 15. The spring wire 18 has a loop 21 formed therein parallel to and ad-

jacent the loop 19. The loop 21 is somewhat longer than the loop 19 and has a loop 22 integrally formed thereon and generally parallel thereto. The loop 22 is slightly longer than the loop 21 and has an arm 23 extending outwardly therefrom terminating in a coil 24 on the outer end thereof.

The spring wire 18 has a loop 25 formed therein oppositely of and the same size as the loop 21. A loop 26 is formed in the wire 18 adjacent the loop 25 and spaced therefrom. The 15 loop 25 has the same length as the loop 21 and the loop 26 has the same length as the loop 22. The loop 26 has an arm 27 extending outwardly therefrom terminating in a coil 28 on the outer end of the arm 27.

A central elongate plastic body B is provided centrally with 20 a pair of male snap members 30 which cooperate with the snap sockets 17 to secure the elongate body B to the body 15. A pair of wings 29 secured to the body B are illustrated in the form of a butterfly in FIGS. 1 and 2, but may have any desired form including costume or genuine jewelry. The wings 29 of the butterfly can be made of white satin with the remaining portions embroidered in black or gold or any other desired decorative design.

In the use and operation of the invention the loops 21, 25 are engaged over the neckband 12 so as to be between the neckband 12 and the neck of the wearer. The body 15 extends 25 in front of the neckband 12 as does the loops 22, 26 with the arms 23, 27 extending up under the collar tabs 13, 14 respectively. With the body 15 positioned centrally between the collar tabs 13, 14 the body B and wings 29 are attached thereto so as to extend over the collar tabs 13, 14 completely covering 30 the body 15 and the wire 18.

Having thus described the preferred embodiment of the invention it should be understood that numerous structural modifications and adaptations may be resorted to without departing from the spirit of the invention.

35. What is claimed is:

1. A necktie comprising a body member, a flexible spring wire secured intermediate its opposite ends to said body member, means on said wire for detachably securing said wire and said body member to the collar of a shirt, a second body 40 positioned to overlie said body member and means detachably securing said second body to said body member including a pair of snap sockets integrally formed in said body member and a pair of male snap members secured to said second body for detachable engagement with said snap sockets.

45. 2. A device as claimed in claim 1 wherein the means for securing said wire to the collar of a shirt includes a pair of oppositely disposed downwardly extending loops adapted to engage behind the neckband of the shirt.

3. A device as claimed in claim 1 wherein a pair of oppositely disposed arms are integrally formed on said wire for extending beneath the collar tabs of the collar.
